BATH BENCH

William R. Brewer, Arleta, Calif., assignor to Hamilton C. deJong (doing business as Safety Brothers), Pasadena, Calif.

Original design application Dec. 15, 1967, Ser. No. 9,803. Divided and this application Oct. 11, 1968, Ser. No. 15,892

Term of patent 14 years

Int. Cl. D6—01

U.S. Cl. D15—8

FIG. 1 is a left side perspective view taken from the front of a bath bench showing my new design;

FIG. 2 is a top plan view thereof;

FIG. 3 is a rear elevational view; and

FIG. 4 is a left side elevational view of the same.

This is a division of application Ser. No. D. 9,803, filed Dec. 15, 1967.

I claim:

The ornamental design for a bath bench, as shown.
